DESIGN FOR A FABRIC DISPLAY SAMPLE CARD

Sydney E. Bender, Brooklyn, N. Y.

Application May 4, 1940, Serial No. 92,163

Term of patent 7 years

To all whom it may concern:

Be it known that I, Sydney E. Bender, a citizen of the United States, residing at Brooklyn, in the county of Kings and State of New York, have invented a new, original, and ornamental Design for a Fabric Display Sample Card, of which the following is a specification, reference being had to the accompanying drawing, forming part thereof.

Fig. 1 is a top plan view of the fabric display sample card, showing my design.

Fig. 2 is an enlarged detail perspective view of one unit thereof.

The rear or backing of the sample card structure is solid and plain.

I claim:

The ornamental design for a fabric display sample card, as shown and described.

SYDNEY E. BENDER.
